BY
Cornelius Zalriski
ATTORNEY

UNITED STATES PATENT OFFICE

130,395

DESIGN FOR A LAPEL BUTTON OR SIMILAR ARTICLE

Stanislaw K. Ostrowski, New York, N. Y.

Application August 29, 1941, Serial No. 103,076

Term of patent 3½ years

To all whom it may concern:

Be it known that I, Stanislaw K. Ostrowski, a citizen of Poland, residing at New York city, in the county and State of New York, have invented a new, original, and ornamental Design for a Lapel Button or Similar Article, of which the following is a specification, reference being had to the accompanying drawing, forming part thereof.

I claim:

The ornamental design for a lapel button or similar article, as shown.

STANISLAW K. OSTROWSKI.
